CLAIM

The ornamental design for the board game, as shown and described.

DESCRIPTION

The claimed board game is used as a table top game with a three-dimensional game area, composed by a base (made of a single piece or from individual components), twenty-four sticks being placed into corresponding receptacles of the base and four sets of tokens (in four different colors). Assembled, the board game provides the possibility to arrange tokens in horizontal (left/right) and vertical (up/down) direction. Each direction extends horizontally over three positions, vertically over three stories (levels) respectively.

FIG. 1 is a perspective view of the board game, showing my new design, being fully assembled;

FIG. 2 is a perspective view of the base of the board game; FIG. 3 is an enlarged perspective view of an individual token; and,

FIG. 4 is an enlarged perspective view of an individual stick.
